United States Patent

Des. 235,483
Patented June 17, 1975

235,483

EAR PLUG

Charles Leight, 5336 W. Pico Blvd.,
Los Angeles, Calif. 90019

Filed Jan. 11, 1973, Ser. No. 322,746

Term of patent 14 years

Int. Cl. D24—04

U.S. Cl. D83—1 J

Fig. 1

Fig. 2

Fig. 3

Fig. 4

FIG. 1 is a rear perspective view of an ear plug showing my new design;

FIG. 2 is a side elevational view thereof;

FIG. 3 is a front elevational view of the inner end of the end of the plug; and

FIG. 4 is a rear elevational view of the outer end of the plug.

I claim:

The design for an ear plug, substantially as shown and described.
